THREAD GUIDE

Wiley B. Roe, Elizabethton, Tenn., assignor to
North American Rayon Corporation, New York,
N. Y., a corporation of Delaware

Refiled for abandoned application Serial No.
164,172, September 16, 1937. This application
February 20, 1940, Serial No. 319,883

3 Claims. (Cl. 242—158)

The present invention relates to an apparatus for collecting thread or yarn and more particularly to a thread guide and device for collecting thread or yarn drawn vertically from the supply spool or bobbin.

One object of the present invention is to provide an improved thread guide that is simple, economical to construct and which will properly guide the thread from the thread supply spool to the winding device.

Another object of the present invention is to provide a novel thread guide which when positioned in proper relation to the thread supply and collecting device will automatically receive the thread whereby it will pass to the point of collection and there be readily drawn onto the collecting device without snarling, knotting or breaking.

Still another object of the present invention is to construct a novel thread guide in the form of a helical convolution having its terminus lying in the same radius as the major portion of the helix.

These and other objects of the present invention will in part become obvious and in part be pointed out in the following specification and appended claims when taken in conjunction with the accompanying drawing.

In the drawing:

Fig. 1 is a diagrammatic showing of the relative position of the parts of the apparatus.

Fig. 2 is a diagrammatic view of a side elevation of one form of collecting apparatus.

Fig. 3 is a similar view of another form of collecting apparatus.

Fig. 4 is a top plan view of the thread guide.

Fig. 5 is a side elevation of the thread guide.

In the drawing, in which like numerals of reference indicate like parts 1 refers to a thread or yarn supply means, which generally consists of a spool of thread or yarn 2, which has been wound thereon during a prior operation. The supply spool 1 is usually placed on its vertical axis for the unwinding of the yarn 2 therefrom.

A collecting device 3 is usually positioned above the supply spool. For purposes of illustration the collection device is shown as a horizontally supported reel on which the thread or yarn from the spool 1 is collected at 4 in skein form. The thread or yarn may be arranged on the reel 3 in diamond formation by guiding it over a stationary bar 11 to a reciprocating traverse bar 5 (Fig. 3) and from there to a reel 3 or by imparting a reciprocating movement to the reel itself. However the collecting means is con-

ventional and forms no part of the novelty of the present invention.

In either event the thread or yarn drawn off the spool 1 is passed through a thread guide 6, which is screw threaded or otherwise supported in any suitable manner or, the apparatus as shown at 7. The thread guide 6 is usually formed of an attenuated wire or strip with an attaching screw thread 8 at one end and a helical loop 9 at the opposite end. The extreme end 10 of the guide is curved in applicant's guide on the same radius as the major portion of the helix and terminated within this radius. The position of the thread guide is of prime importance if the thread guide is to automatically pick up the thread. The helix of the thread guide is positioned so that the axis of the helix coincides with the axis of the supply spool from which the thread is generally drawn as shown in Figures 1, 2 and 3 of the drawing. The drawing off point above the thread guide is also in line with the axis of the helix of the guide and the axis of the vertical spool so that a center line drawn through the supply spool, the helix of the thread guide and the drawing off point above the guide all coincide.

In Figure 2 the point of collection is the outer periphery of the reel itself with the axis of the thread guide and supply spool tangential to the said periphery.

In Figure 3, in which form a traverse guide is used in order to impart the desired cross wind on the collecting reel, a guide rod for changing the direction of travel of the thread has its periphery positioned in such a way that the axis of the supply spool and helix of the thread guide is tangential thereto.

With the thread guide in proper relative position to the take-off point above the supply spool below, as just described in the foregoing paragraph, it is also essential to have the thread unwind from the supply spool in the direction of rotation which coincides with the direction of twist of the helix. By so doing it is obvious that the thread will be drawn into the guide without further assistance from the operator of the machine provided the extreme end 10 of the guide is curved on the same radius as the major portion of the helix and terminated within this radius. If, as is usual in guides of this kind, the end of the guide extends beyond the radius or rest of the helical portion of the guide it is impossible that the thread feed automatically without aid within the guide.

It has been found unexpectedly that a thread

guide whose helical portion consists of one and one quarter turns, as shown at 9 in the accompanying drawing, yields more satisfactory results than can be obtained with the conventional type of thread guide. Experiments have shown that the thread guide disclosed in the present invention is most suitable for automatically receiving the thread and for retaining it well within its confines during the ballooning action of the thread.

In operation the operator takes the free end of the thread 2 from the supply spool and passes it upwardly around the bars of the reel 3 and as the yarn starts to unwind in the same direction as the twist of the helix of the thread guide it will be automatically thrown therein so that there is no need for the operator to take the additional step of inserting a thread into the helix of the guide as is usual in the winding operation. Further it is obvious that it is impossible with a guide which automatically picks up the thread at the start of the operation to lose the thread during the whole winding operation.

When the supply spools 1 are positioned on a twisting machine and revolved at a very high rate of speed the thread balloons away from the spool even more so than in the ordinary winding machine but it will be found that applicant's novel guide will still pick up the thread automatically and hold it securely within the confines of the helix throughout the entire twisting operation.

Whether the thread is unwound from a stationary supply spool or whether it is unwound from a rotating spool there is still the resulting balloon like effect as the thread unwinds and it is therefore essential that a guide be placed above the supply spool in order that the thread can be constantly drawn from a single point and will not slip on the guide rod or on the traverse bar. 40

The foregoing apparatus, therefore, not only prevents snarls, thread breakage and the like, but because the thread is unable to slip out of the thread guide a more perfect guiding operation is achieved as well as less attention required by the operator.

This application is a substitute for application

Serial No. 164,172 for Thread guide filed September 16, 1937.

What I claim is:

1. In a thread winding apparatus, in combination a vertically supported thread storage device from which thread is drawn endwise, a thread drawing-off point, a self-threading guide positioned between said storage device and said drawing-off point and in axial alignment with said storage device, and means for bringing said thread drawing-off point into axial alignment with said thread storage device and said thread guide, said thread guide comprising an attenuated member having one terminal end thereof fixed to supporting means with the opposite terminal end thereof extending into the path of travel of the thread drawn between said thread storage device and said thread drawing-off point, said opposite terminal end being coiled in the form of a helix having a twist coinciding with the direction of rotation imparted to said thread during the drawing thereof and convolutions spaced sufficiently apart from said attenuated member and pointing towards said drawing-off point to automatically draw and retain said thread therein when said thread storage device, said drawing-off point and the helix of said thread guide are brought into axial alignment upon drawing said thread from said thread storage device to said drawing-off point, said helix being coiled about one and one quarter turns and the terminus thereof being curved in the same radius as the major portion of the helix and terminated within said radius.
2. A thread winding apparatus as set forth in claim 1 in which the means for bringing said thread drawing-off point in axial alignment with said thread storage device and said thread guide include a horizontally supported, reciprocating reel.

3. A thread winding apparatus as set forth in claim 1 in which the means for bringing said thread drawing-off point in axial alignment with said thread storage device and said thread guide include a reciprocating traverse bar.
